UNITED STATES PATENT OFFICE.

CLAES RYDEN, OF CRANSTON, RHODE ISLAND.

WIRE-WINDING DEVICE.

1,172,565.

Specification of Letters Patent. Patented Feb. 22, 1916.

Application filed March 23, 1915. Serial No. 16,458.

To all whom it may concern:

Be it known that I, CLAES RYDEN, a citizen of the United States, residing at the city of Cranston, in the county of Providence and State of Rhode Island, and whose post-office address is 106 Massasoit avenue, in said city, have invented certain new and useful Improvements in Wire-Winding Devices, of which the following is a specification.

10 My invention relates to an improved device adapted for use in winding wire to form electric coils, and for filling supply bobbins.

The invention consists of a swinging frame carrying an idler wheel and a delivery wheel, both said wheels designed to traverse together in delivering the wire around a revolving spindle, slideable stop-pieces to limit the traverse movement of said wheels, means to respectively permit 20 the wire to feed in straight layers, length-wise of the spindle, each layer having an equal number of turns, to form a coil having flat sides, and to feed in such manner that the turns of one layer come between the 25 turns of the next contiguous layer, to form a coil having tapering sides, and means to regulate the distance of traverse movement of said wheels.

In the accompanying two sheets of drawings, wherein like reference characters indicate like parts, Figure 1 is a front elevation of my improved wire-winding device. Fig. 2 is an end view of the same. Fig. 3 is a plan sectional view of the device, showing the 35 relative position of parts, as at the completion of one style of electric coil. Fig. 4 is a rear view of the device, showing a screw-shaft for regulating the traverse movement of the wire guide wheel and the delivery 40 wheel. Fig. 5 is an enlarged section taken on line $x-x$ of Fig. 3, showing how the wire layers are built up to form a coil. Fig. 6 is a front view of the wire guide wheel and the delivery wheel, partly in section and 45 illustrating how both said wheels are caused to traverse together in the feeding movement of the wire. Fig. 7 is a cross section of the device, taken on line $y-y$ of Fig. 3, showing the course the wire takes by the revolving spindle. Fig. 8 is a sectional view taken 50 on line $w-w$ of Fig. 1, showing means to

permit the device to operate in feeding the wire to form a coil of the style illustrated in Fig. 10. Fig. 9 shows a latch member for holding the rack bar free of engagement 55 with a pinion fast on the screw-shaft. Fig. 10 shows a coil formed with a succession of shorter layers, offset from each other, to form a coil having tapering sides. Fig. 11 is a rear view of the device, showing a scale 60 plate to reveal the distance of traverse movement of the wire, and, Fig. 12 is a cross-section taken on line $z-z$ of Fig. 11.

In carrying out my invention I employ a standard $-a-$ which is secured upon a 65 table, by means of bolts $-a^1-$. A vertical frame $-b-$ is pivotally mounted on a horizontal shaft $-b^1-$ fixed at the lower part of the standard, and said frame carries at its upper part horizontally-arranged rods, 70 $-b^2-$, $-b^3-$ and screw-shaft $-b^4-$. The rods $-b^2-$, $-b^3-$ are fixed to the frame, and on the former rod is a slideable wire guide wheel $-c-$, which has flat projecting flanges $-c^1-$ designed to have a sliding fit 75 upon the side faces of a wire delivery wheel $-d-$, slideable on the rod $-b^3-$. The web $-d^1-$ of the wheel $-d-$ is of a thickness equal in the diametrical size of wire for feeding to form the coil. Each wheel $-c-$ and 80 $-d-$ is peripherally grooved to receive the wire $-e-$ and provided with rollers $-c^2-$ (see Fig. 3) to lessen the friction in the lateral movement of said wheels. On the standard $-a-$ is a horizontal spindle $-f-$ 85 which is driven by power through a belt connection with a pulley $-f^1-$ fast on said spindle.

The wire in feeding by my improved device comes from an overhead tension reel 90 (not shown,) and passes under the guide wheel $-c-$, over the delivery wheel $-d-$, from whence it is carried under and around the power driven spindle $-f-$, in the manner clearly illustrated in Fig. 7. 95

In the wire-winding formation $-e^1-$, shown in Figs. 1, 3 and 5, flat disk members are fixed on the spindle, to serve as head pieces $-f^2-$ in building up this style of coil, to have opposed straight sides, as shown 100 in said figures.

The shaft $-b^4-$ has right and left hand

screw-threaded portions in engagement with the nut ends g^1 of stop pieces g , which are perforated to loosely receive the rods b^2 , b^3 , and said shaft is provided with a knurled head b^5 to grasp upon in positioning said pieces g the proper distance apart for the traverse movement of the feed wire.

In starting to build up a coil, as in Fig. 5, 10 after the first traverse movement of the wire has been made by the spindle, to form the inner layer, as at a point e^2 , the head piece f^2 causes the feed wire to move outwardly and directly upon the last 15 turn made in said layer, thus the frame b is made to swing back in the direction indicated by the arrow shown in Fig. 2, this slight rearward movement being equal to the thickness of the feed wire, to make the 20 next return traverse layer.

On the standard a is secured a rod h which has pull-spring connections i with the frame b , for holding the wheel d close to the spindle.

Having the guide wheel c arranged to embrace the delivery wheel d , in the manner shown in Fig. 6, permits the wire to feed in alinement with the peripheral centers of both said wheels, and thereby the 30 wire is enabled to form its succession of layers evenly throughout the feeding operation to form the coil.

In Figs. 8 and 9 I show a means whereby my improved device is adapted to operate 35 the wire in feeding to build up a coil to have opposed tapered sides, as in Fig. 10.

Pivoted on the standard a is a rearwardly extending rack bar j for engaging a pinion k , fast on the screw-shaft b^4 . A spring l is secured on the standard and has its free portion in yielding contact with the rack bar j , for holding the latter in mesh with the pinion k . A flat leaf spring member m is vertically 45 secured on the standard a , and said member, which forms a finger latch, has a lug m^1 to bear upon the top of the rack bar j , for holding the latter out of engagement with the pinion, during the time 50 the device operates to form the style of coil shown in Fig. 5.

To operate in forming the style of coil shown in Fig. 10, the latch m is pressed upon to allow the spring l to force the 55 rack bar j into engagement with the pinion.

On the spindle f is secured a tubular member n for the wire to feed upon, and said member has its ends upturned, as 60 at n^1 , in order that the first formed wire layer e^2 may be held evenly throughout its course around the said member n . At the moment this first or inner layer e^2 is formed a slight rotation

is imparted to the screw-shaft b^4 , 65 through the pinion k , by virtue of the diametrical size of the feed wire in starting to make the next traverse layer in the coil, thus the wire is made to feed directly between the turns of the wire forming each 70 layer, and each rotary movement of the shaft b^4 and pinion k causes the wire to alternately lessen its number of turns throughout the series of layers, and thereby forming a coil having opposed 75 tapered sides, in the manner shown in Fig. 10.

Short expanding coil springs encircle the rod b^2 , to form buffers, as at p , to assist the wheels c , d in the initial movement of the wire in feeding to form 80 each layer.

To determine the exact distance of traverse movement to form the inner layer e^2 , in building up of a coil, a plate r is secured across the back of the frame b 85 and provided with graduation marks, as at r^1 , and by turning the screw-shaft a pointer, which is carried by one of the stop pieces, as at s , is brought to the index mark of the scale and the measured distance had for the device to operate in forming the desired width of coil.

What I claim and desire to secure by Letters Patent, is,—

1. In a device of the character described, 95 a standard, a revolving spindle mounted on the latter, means secured on the spindle to limit the length of traverse to form the inner wire layer, a pivotal frame carrying a guide wheel and a delivery wheel, both said 100 wheels constructed to traverse laterally together in feeding the wire about the spindle, a shaft mounted on the frame and having right and left hand screw-threaded portions, stop pieces having nut ends engaging 105 the threaded portions of said shaft, yielding means to hold the frame toward the spindle, a pinion carried by the said shaft, a rack bar pivoted on the standard, means to hold said bar in engagement with the 110 pinion during the operation of forming a coil with tapered sides, and means to prevent rotation of the screw-shaft during operation to form a coil with straight sides.

2. In a device of the character described, 115 a power-driven spindle, a tubular member fixed upon the latter and having upturned ends, to receive the winding feed wire in the form of a straight layer therebetween, a pivotal frame carrying a wire delivery 120 wheel and a wire guide wheel embracing the latter, to permit the wire to feed in direct alinement with the peripheral centers of both said wheels in forming the respective layers about said tubular member, a shaft 125 having right and left hand screw-threaded portions, stop pieces in engagement with the threaded portions of said shaft, to limit

the traverse movement of both said wheels, means to impart a slight rotation of said shaft, in the initial feed of the wire to form the next contiguous layer, and to permit
5 the wire to feed between the turns of the latter, in forming a coil to have opposed tapered sides.

In testimony whereof I affix my signature in presence of two witnesses.

CLAES RYDEN.
